UNITED STATES PATENT OFFICE

2,183,352

ILLUMINATING MEANS FOR SIGNS AND SHOWCASES

Frank J. Hoke, Brendenwood, Ind., assignor to
Holcomb & Hoke Manufacturing Company,
Indianapolis, Ind., a corporation

Application December 19, 1938, Serial No. 246,586

1 Claim. (Cl. 40—130)

This invention relates to a refrigerated showcase, particularly to a display feature thereof embracing illuminated advertising panels.

The object of the invention is to provide a refrigerated showcase with conveniently located advertising panels so positioned with respect thereto as to be generally in the line of vision of the customer, but without obstructing the customer's view of the contents on display within the case, and wherein the advertising panels are so arranged as to be illuminated by the same source of illumination as the contents displayed within the case. Furthermore, such panels are built in as a decorative part of the structure without interfering with the normal or usual structure or functioning of the case of which they form a part.

One embodiment of the invention resides in the provision of a decorative apron formed as a portion of the top of the casing and extending downwardly with respect to the glass front, such apron carrying one or more apertured panels in the forward face thereof which provide frames for illuminated advertising plates, such as colored glass or the like. Associated with each of the panels and hidden by the apron and plates is a source of illumination, such as electric light bulbs which may be supported in position to be hidden from view while acting to illuminate both the panels and products contained within the case.

Other objects and features of the invention will be understood from the accompanying drawing and the following description and claim:

Fig. 1 is a central vertical section through a refrigerated display case embodying the invention. Fig. 2 is a front elevation thereof. Fig. 3 is an enlarged section through one of the advertising panels.

In the drawing there is shown as one embodiment of the invention a refrigerated case having a base 10, a front wall 11 and a pivotally mounted door or closure 12 for giving access to the lower compartment of the case. The lower compartment is separated from the upper compartment by a display shelf 13 for supporting products displayed therein through the transparent front panel 14. The upper rear portion of the case is provided with sliding doors 15 for giving access to the upper compartment into which there extend shelf-supporting brackets 16 and refrigerant units, indicated at 17. The transparent front panel 14 is formed in the usual manner with a series of glass plates spaced from each other by their supports comprising end walls 18, a top frame member 19 and the front wall 11.

A top frame structure 20 is covered as usual with enamel finished sheet metal 21. As shown more clearly in Fig. 3, the sheet metal top covering extends forwardly beyond the top frame

member and structure 19 and 20 and is then extended downwardly a short distance to provide a depending apron 22 extending the full length of the case and spaced forwardly from the plane of the transparent front panel 14. In the forward face of the apron 22 there are provided a series of longitudinally extending apertures 23. Behind each of the apertures and between the apron and the top frame member there are supported a plurality of electric lamps indicated at 24, said lamps being supported from a bracket 25 secured to a mounting strip 26 extending along the forward face of the frame member 19. Each of said lamps is thus positioned so that the light emanating therefrom will be directed through the corresponding apertures 23 and through the glass front 14 to the interior of the case. The lateral rays from said lamps are further augmented by reflection from the interior surface of the apron 22 and the lower reflecting surface 20 of their supporting brackets 25. For the prevention of shadows being reflected from the glass front 14, the apron 22 is curved inwardly at its lower edge, terminating in an upwardly turned flange 27 positioned below the lamps. At each end of the case there is an outwardly extending end flange 28 having its forward edge merging into the exposed surface of the front wall 11 and the front surface of the apron 22.

Mounted over each of the apertures 23 there is a display frame 29 removably supporting therein a transparent display panel 30. Said display panel is preferably formed of colored glass having advertising displays so formed or arranged as to be illuminated by the lamps 24 through the apertures.

By means of this arrangement, the same source of light will illuminate the contents of the case and the advertising panels, the advertising panels 40 being attractively arranged directly in the line of vision of the customer and embodied in a structural part of the case which at the same time serves as a reflector and as a shade.

The invention claimed is:

A showcase including a flat top and a transparent front panel, a plate lying flat upon said top and extending in a continuous unbroken horizontal plane from the rear to the front thereof and projecting beyond the front edge of said top, 50 an apron formed integral with said plate and depending therefrom beyond the forward edge of said top, said apron having an aperture therein with its upper edge disposed a substantial distance below said plate, an advertising panel 55 mounted on said apron over said aperture, and a light source between said panel and said apron wholly concealed by the latter and disposed behind said advertising panel.
